FLOOR PROTECTING SHEET FOR
RAILWAY CARS

Charles D. Bonsall, Chicago, Ill., assignor, by
mesne assignments, to Standard Railway
Equipment Manufacturing Company, a corpora-
tion of Delaware

Application August 25, 1943; Serial No. 500,182

4 Claims. (Cl. 105—422)

The invention relates to railway freight cars of the house or roofed type and has for its object to provide means for protecting the wooden floors now in general use in such type of equipment, which means will not interfere with the securing of blocking to the wooden flooring.

Another object is to protect the wooden flooring with a metallic sheathing which is perforated so that the car lading may be secured to the flooring through the apertures.

The floors of railway cars are subjected to a great deal of abuse by nails and spikes being driven into them when attaching blocking to them, and also by trucking the lading into the car and by dragging pieces of lading from one part of the car to another. That portion of the car between the opposite side wall doorways is given the most abuse by lading being hauled through the car (by truck or otherwise) to an adjacent car. However, my improved floor protection may be applied over the entire area of the floor if desired.

Another object is to provide the floor sheathing with an extension to cover and protect the part of the wooden flooring between the side door posts of the railway car, which part forms the threshold of the doorway. The threshold is subjected to a great deal of abuse and wear by the above mentioned trucking.

The lower portions of the door posts are subjected to considerable damage by the wheels and sides of the freight handling trucks hitting the posts as they are rolled in or out of the car, therefore, another object of the invention is to also provide the floor sheathing or floor protecting sheet with means to protect the lower portions of the door posts.

Another object is to provide a floor protection which may be easily installed and parts of which may be easily removed and replaced when it is desired to repair the floor.

Other objects and advantages of my invention will be apparent from the following detailed description by referring to the accompanying drawings.

In the drawings:

Fig. 1 is a cross section through the lower part and doorways of a railway car provided with my improved floor protecting sheet.

Fig. 2 is a section through the door posts and doorway looking down on the floor protecting sheet.

Fig. 3 is a section through the doorway at the side sill showing the floor protecting sheet and associated parts.

Fig. 4 shows a separate door post protecting plate.

Fig. 5 is a perspective view of the improved floor protecting sheet, per se.

Fig. 1 shows the wooden floor 2; door posts 3; doorway threshold 4; center sills 5; side sills 6; floor protecting sheet 7 and the attaching bolts 8.

The protecting sheet 7 is provided with a plurality of apertures 10 so that the car lading may be secured to the wooden flooring 2 through said apertures.

The floor protecting sheet 7 preferably extends between the doorways on opposite sides of the car and protects both thresholds 4—4.

The protecting sheet 7 extends between the door posts 3 on opposite sides of the doorway so as to protect the part of the wooden flooring forming the threshold of the doorway and is preferably formed with a downturned stiffening flange 12 which also protects the edges of the wooden floor boards 2 from abrasion and the weather.

The portion of the protecting sheet between the door posts is provided with an upstanding flange 14 adjacent each door post to protect the lower part thereof. These flanges are adjacent and secured to the sides of the door posts 3 facing the doorway preferably by welded material, or if desirable, the bolts 15.

The protecting sheet 7 is also provided with an upstanding flange 16 adjacent and secured to the sides of the door posts 3 facing the interior of the car. These flanges 16 are preferably integral with the flanges 14 secured to the sides of the posts facing the doorway. Preferably these flanges 14 and 16 are welded together and to the door posts 3 after in place on the car.

Fig. 4 shows a door post protecting plate 18 covering the lower portion of each door post which is preferably welded to the posts 3 and protecting sheet 7. This plate 18 comprises flanges 19 and 20 corresponding to 14 and 16, respectively, and also a flange 21 for attachment to the floor protecting sheet 7.

The upstanding flanges 14 or the protecting sheet 7 may be extended to engage and be secured to the front (23) and rear (24) door weather strips by welded material. These weather strips are secured to their respective door posts.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a railway car having spaced apart door posts and weather strips secured thereto with a doorway therebetween and a wooden floor, said floor extending between said posts and weather strips to form a threshold for the doorway; a floor protecting sheet covering said floor and provided with apertures therein so that the car lading may be secured to said flooring through said apertures, said protecting sheet extending between said door posts and weather strips to protect said threshold and extending beyond said door posts and being downwardly turned to provide a protecting flange for the outer edge of the threshold, said protecting sheet provided with upstanding flanges secured to the sides of the door posts facing the doorway and to said weather strips, and other upstanding flanges secured to the sides of the door posts facing the interior of the car.
2. In a railway car having spaced apart door posts and weather strips secured thereto with a doorway therebetween and a wooden flooring extending between said posts and weather strips to form a threshold for the doorway; a floor protecting sheet covering said floor and provided with apertures therein so that the car lading may be secured to said flooring through said apertures, said protecting sheet extending between said door posts and weather strips to protect said threshold, and a door post protecting plate covering the lower portion of each door post and weather strip and welded to said protecting sheet and to said posts respectively.

3. In a railway car having spaced apart door posts and weather strips secured thereto with a doorway therebetween and a wooden flooring extending between said posts and weather strips to form a threshold for the doorway; a floor protecting sheet covering said floor and provided with apertures therein so that the car lading may be secured to said flooring through said apertures, said protecting sheet extending between said door posts and weather strips to protect said threshold, and a protecting plate secured to said protecting sheet and to the side of the post and weather strip facing the doorway and to the side of the post facing the interior of the car.

4. A floor protecting sheet for a railway car having spaced apart door posts forming a doorway therebetween, weather strips secured to said posts in the same transverse plane and a wooden floor extending between said posts and weather strips to form a threshold for the doorway; said floor protecting sheet covering said floor and extending between said door posts to protect said threshold, said sheet having a downturned stiffening flange extending the full length of said threshold to protect the edge of said wooden floor from abrasion and weather, and upstanding flanges extending at right angles to each other and secured to opposite corners of said sheet for attachment to and protection of the lower part of said door posts and weather strips.

CHARLES D. BONSALL.
